IRV E. McCABE, OF CHICAGO, ILLINOIS.

TEMPERATURE-ACTUATED ELECTRIC CONTROL DEVICE.

Application filed November 3, 1925. Serial No. 66,518.

This invention relates to improvements in electric control devices and more particularly to a temperature actuated electric control device.

5 In many instances electrically operated devices are employed in the production of heat and in the electric circuit of such a device it is desirable to provide a control for starting and stopping the operation of such a device, 10 which control is actuated by the temperature created by the operation of said device.

It is the object of this invention to provide a device of this character and an embodiment of this device is particularly illustrated and 15 described as adapted for use in an electrically operated furnace or heat producing device and which is particularly advantageous as a part of an electrically operated liquid fuel burner system for domestic purposes, al- 20 though this invention contemplates other uses of this control. It is a further object to provide a device of this character which is particularly adapted in electrically operated domestic liquid fuel burning systems to 25 act as a safety device for such systems. The particular embodiment of this invention as illustrated on the accompanying sheets of drawings and hereinafter described is de- 30 signed to be applied to the stack or pipe lead- 35 ing from the furnace heated by the domestic liquid fuel burner system which will operate to break the electric circuit in case the liquid fuel burner does not ignite or if the flame from the burner fails at any time after igni- 40 tion.

In the drawings:

Figure 1 is a view in the front elevation of the casing, with the cover removed, illustrating an embodiment of this invention and 45 illustrating in diagram the wiring between this device and the electric motor.

Figure 2 is a view in horizontal section taken on the line 2—2 of Figure 1 looking in the direction of the arrows.

45 Figure 3 is a view in the side elevation of Figure 1 with parts broken away and partly in section.

Figure 4 is an enlarged detailed view in 50 central vertical section of the heating element illustrated in Figure 3.

Figure 5 is a view in diagram illustrating the application of a modified form of this control actuating the electric connections between an electric motor and the source of com- 55 mercial current.

In the embodiment of this invention as illus-

trated in Figures 1 to 4 inclusive, the electric circuit to the motor is closed or opened by the tilting movement of a mercury tube switch 1, which is shown mounted on a pivoted carrier plate 2, with two terminals adjacent each other and near one end of the tube so that when the tube is tilted in that direction the mercury will accumulate in that end and close the circuit through such terminals and 60 when tilted in the opposite direction the mercury will flow away from said terminals and break the circuit therethrough. As shown in Figures 1 to 3 the tilting plate 2 carrying the mercury tube is provided with a counter-weight 3 which will normally tilt the tube to the open or circuit-breaking position. The plate 2 carrying the mercury tube is also provided with a depending projection in the form of a pawl 4 adapted to engage in the teeth 70 of a ratchet wheel 5 carried by a sleeve 6 having a detachable connection with an enclosed shaft 7 whereby the mercury switch tube may be tilted into the closed position and held therein against the counter weight by engagement of the pawl with the ratchet and which when the ratchet carrying sleeve becomes detached from the shaft will allow the counter-weight to cause the ratchet to be rotated by 75 the pawl releasing the tilting plate 2 and moving the switch tube into the open position. 80

As illustrated in Figure 4, the sleeve 6 carrying the ratchet wheel 5 is of greater inside diameter than the outside diameter of the fixed shaft 7 which it surrounds and the 85 lower end of the sleeve is received in a cup shaped enlargement of said shaft as shown. The space between the inner circumference of the sleeve and the outer circumference of the shaft is filled with solder which will normally secure the sleeve in the fixed position upon the shaft. The shaft, 7, is preferably 90 constructed of brass or other heat transmitting metal and is rigidly secured upon a bracket 8 of similar metal. This bracket has 95 a depending portion 9, forming one end of the heat generating unit which when actuated to generate heat will transmit the heat so generated through the bracket to the shaft and melt the solder allowing the sleeve to be ro- 100 tated about the shaft.

The heat generating unit is preferably composed of two or more series of loosely mounted superimposed graphite disks 10 arranged side by side in a cylinder 11 of lavite 110 or other electric insulating material with one end bearing against the depending heat trans-

mitting bracket 9, and the other end bearing against a movable block 12 held in place and movable between four posts 13 securing the heat transmitted bracket to the back of the 5 instrument casing. A sheet of mica or other electrical insulating material 14 capable of transmitting heat is interposed between the series of graphite disks 10 and heat transmitting bracket 9 at one end and the movable 10 block 12 at the other end, it being preferable to provide a metallic disk 15 with a centering projection between the movable block 12 and the adjacent series of graphite disks 10.

As seen from Figure 3, a sleeve 16, is arranged to project from the instrument casing at the back of the movable block 12 and be secured to the stack or pipe 17 extending from the furnace to the smoke stack or chimney. Arranged in line with the center of the 20 movable block 12 is a tubular member 18 of metal adapted to extend within the stack and be secured to the instrument supporting sleeve 16, preferably by means of a split sleeve 19 secured to the said supporting 25 sleeve 16. Within this tubular member 18, is arranged a metallic rod 19, which is secured to the extremity of the tubular member within the stack. It is preferable to construct the tubular member 18 and the rod 30 19 of metals of different co-efficients of expansion, such as constructing the tubular member of iron or steel with the enclosed rod of brass, copper, or aluminum, whereby the heat arising from the furnace and passing 35 through the stack about the tubular member will cause the same to expand and cause the enclosed metallic rod to expand to a greater extent. In line with this rod 19, and the center of the metallic block is mounted 40 a movable plunger 20 having a reduced portion 21 adjacent its end nearest the movable block forming shoulders on each side thereof which reduced portion is mounted to extend through a plate 22 secured by the four 45 heat supporting unit posts 13 to the back of the instrument casing which plate will be engaged by the shoulders and limit the movement of the plunger toward and away from the movable block. The expansible rod 50 19 carried within the tubular member and secured at one end thereto is provided with a reduced free end or a small concentric rod 23 secured thereto the free end of which is adapted to slide within a recess 24 in the adjacent end of the plunger 20. The upper 55 portion of the plunger adjacent its free end is cut away to receive a clamping member 25 adapted to bear upon the upper side of the reduced end 23 of the rod 19 which clamping member is held under tension by a spring 26 carried upon the upper side of the plunger, the tension of which is adjusted by a bolt and nut passing through the plunger. As 60 seen from Figure 4 the movable block 12 is 65 provided with a screw threaded abutment 27

passing through the center thereof and adapted to engage the adjacent end of the plunger 20 so that by adjustment of this abutment the amount of pressure applied by the forward movement of the plunger before 70 its rear shoulder is engaged by its supporting plate transmitted through the movable block to the series of graphite disks may be regulated. The tension of the spring clamp 25 in engagement with the free end of the 75 expansible rod 19 is such that, if the plunger 20 be retracted with the forward shoulder in engagement with the supporting plate with the expansible rod in its contracted position and the tubular member within the 80 stack is subjected to an increasing temperature, the first expansion of the rod will push the plunger 20 forward against the movable block 12 transmitting pressure upon the series of graphite disks 10 until the rear shoulder 85 of the plunger engages its supporting plate, and a continued expansion of the rod 19 will cause its reduced end 23 to slide under the clamping member 25, and upon the contraction of the rod it will first withdraw 90 the plunger 20 until its forward shoulder engages its supporting plate and then continued contraction will cause the reduced end 95 of the rod to slide under the plunger carried clamp.

As shown in Figures 1 and 3, four binding posts, 28, 29, 30, and 31, are provided upon the rear of the instrument casing above the mercury tube switch. The two upper binding posts 28 and 29 are secured by flexible 100 leads 32 to the terminals of the mercury tube switch. The left hand binding post 28 of the upper series is connected by a lead 33 to the outermost graphite disk, of one series, the rearmost graphite disk of that series being 105 connected by a lead 34 to the corresponding rearmost graphite disk of the other series and the outermost graphite disk of said latter series is connected by a lead 35 to the lower left hand binding post 30. From the 110 diagram of the wiring shown in Figure 1, it is seen that one line of the outside source of electricity or commercial circuit is connected to the upper right hand binding post 29 of the instrument casing and the other line 115 of the commercial circuit is connected to one pole of an electric motor, M, the other pole of which is connected to the lower left hand binding post 30 on the instrument casing. The mercury tube switch is shown in the closed position so that the circuit from the outside will pass through the upper right hand binding post 29 through the lead 32 therefrom to the switch, the mercury within the switch, the lead 32 from the other terminal of the switch to the upper left hand binding post 28 and from thence through the lead 33 to one series of the graphite disks, through that series of graphite disks, through 125 the lead 34, therefrom to the other series of 128

graphite disks, through the latter series of graphite disks to the lead therefrom to the lower left hand binding post 30, and from thence through the motor, M and back to the source of commercial current. It is readily seen that when sufficient heat is generated by the current passing through the graphite disks to melt the solder to release the ratchet wheel, the counterweight will tilt the mercury tube switch to cause the mercury to flow to the opposite end and thereby break the electrical circuit through the switch which will also break the circuit through the motor.

In the electrical art it is recognized that series of superimposed graphite disks, such as shown and described, will transmit electricity and generate heat in proportion to the amount of pressure applied to such series of disks, the greater the pressure the greater ease the current passes through the series and the less amount of heat generated. By a proper adjustment of the abutment 27 of the movable block 12 of the heat unit shown and described, an amount of pressure can be applied to the series of graphite disks to normally generate heat sufficient to melt the solder normally securing the ratchet wheel in the fixed relation to the immovable shaft and by providing a proper number of graphite disks in each series sufficient pressure may be applied thereto by the normal extended movement of the plunger 20 to allow the current to pass through the disks without generating sufficient heat to melt the solder.

By the construction shown in Figures 1 to 4, it will be readily seen that as soon as sufficient heat has passed by the tubular member 18 within the stack to move the plunger 20 it compresses the graphite disks sufficiently to prevent the solder melting and when such heat ceases or diminishes sufficiently to cause contraction of the metallic rod 19 such pressure upon the disks will be immediately released and sufficient heat will be produced by the disks which will be transmitted through the heat transmitting bracket 9 to the post 7 within the ratchet wheel sleeve 6 to melt the solder, allowing movement of the ratchet wheel whereby the counterweight 3 through 2 will rotate the ratchet wheel 5 and tilt the mercury tube switch to the opposite or open position.

As above stated, this device may be most advantageously used to control electric circuits for actuating an electrically operated domestic liquid fuel burner and by proper adjustments the closing of the circuit, with the mercury tube switch in the closed position, will ignite and operate the domestic burner and the heat arising from the burner flame will be sufficient to expand the metallic rod to compress the graphite disks before sufficient heat has been generated to melt the solder holding the ratchet wheel in the fixed rela-

tion, and upon failure of the burner flame the cooling of the tubular member will be quickly transmitted to relieve such pressure upon the graphite disks causing sufficient heat to be generated thereby to quickly melt the solder 70 and release the ratchet wheel to break the motor circuit.

In the modification shown in Figure 5, the variation of pressure upon the series of similar graphite disks 10 is employed in connection with the type of mercury tube switch shown and described in my prior application filed March 30th, 1925, Serial No. 19,310, in which a similar mercury tube switch 1, is mounted upon a tilting plate 2, pivoted to the rear of the instrument casing provided with a similar counter weight 3, upon the switch carrying plate and pawl and ratchet wheel attachment 4 and 5 similar to that heretofore described, with the difference that the fixed post 7 within the ratchet sleeve 6 is heated by a coil of resistance wire 40 wrapped thereabout as shown in Figure 5, instead of the heat being transmitted by the supporting bracket 9 as described in connection with Figures 1 to 4. A separate mechanism in a casing is provided to be attached to the stack or pipe 17 leading from the furnace to the chimney or smoke stack, including a tubular member 41 of rapidly expandible metal, such as copper, brass, or aluminum, adapted to be extended in the stack or pipe and secured thereto by a flanged plate 42 as illustrated. A rod 43 of steel, or iron, or less rapidly expandible metal, is secured to the end of the tubular member within the stack, the free end of which rod passes through a sleeve 44 having a flange 45 about one end adapted to be secured upon the inner side of the mechanism casing with the exterior portion 46 of the sleeve reduced and adapted to slide within the tubular member and prevented from rotation thereabout by a pin 47 passing through this reduced portion, through a slot 48 in the rod, and through opposite disposed slots 49 105 in the surrounding tubular member with the ends of the pin engaged in a split sleeve or clamp 50 arranged about the exterior of that end of the tubular member 41. The end of the rod within the instrument casing passes 110 through and is adjustably secured to a pressure plate 51 extending over one or more series of graphite disks, 10 contained within cylinders 11 of lavite or other insulating material, which cylinder engages the supporting sleeve flange 45, within the instrument case and are electrically insulated therefrom by a disk or sheet 52 of mica. Secured to the adjacent side of the pressure plate 51 a pressure member 53 is provided which is adapted to 115 engage the series of graphite plates thereunder within the insulating cylinder 11 at various pressures and is insulated from such series by a sheet or disk 54 of mica or other insulating material.

The slot 48 within the rod 43 allows a little play within the supporting sleeve 44 so that upon heat of increasing temperature passing about the tubular member 41 within the stack 5 will first cause the tubular member 41 to more rapidly expand than the rod 43 contained therein which will cause a pulling action upon the rod which will exert pressure through the pressure plate 51 upon the series 10 of graphite disks 10 until the left hand end of the slot 48 in the rod engages the sleeve centering pin 47 and further expansion of the tubular member will cause the instrument supporting sleeve 44 to be drawn within or 15 the surrounding tubular member 41 against the tension of the surrounding clamp 50 so that as soon as the temperature of the stack diminishes the tubular member will begin to contract and the contraction will cause immediate 20 movement of the rod in the opposite direction, thereby releasing the pressure upon the series of graphite disks, and further contraction will cause the instrument supporting sleeve 44 to be pushed outward from the end 25 of the tubular member against the tension of the pin supporting clamp 50. It will be seen in Figure 5 that the uppermost instrument casing is provided with three binding posts 55, 56, and 57, the upper one 55 of which 30 is connected by a lead 58 to one end of the upper series of graphite disks with the other end of such series connected by a lead 59 to the middle binding post 56 which in turn is connected by a lead 60 to one end of the second 35 series of graphite disks with the other end of such series connected by a lead 61 to the lower binding post 57. In the instrument casing at the bottom of Figure 5 it is seen that the two uppermost binding posts 62 and 40 63 are connected by flexible leads 64 to the respective terminals at one end of the electrical tube switch 1 adapted to be placed in the circuit by the mercury accumulated at that end of the tube. The upper right hand 45 binding post 63 is connected by a lead 65 to the upper of the lower series of binding posts 66 and 67 which in turn is connected to the resistance wire 40 passing about a depending extension of the shaft 7 with the other 50 end of such resistance wire 40 connected to the lower binding post 67 of this series. From the diagrammatical illustration of the wiring shown on Figure 5, it is seen that one line of the commercial source of electricity 55 is connected to the upper left hand binding post 62 so that the current passing therethrough will pass through the mercury tube switch, in the position illustrated in Figure 5, to the other upper left hand binding post 63 and then through lead 65 binding posts 66 and resistance wire 40 about the heating element of the solder retaining ratchet wheel to the lowermost binding post 67 of that series which in turn is connected to one 60 pole of an electrical motor M, the other pole 65

of which is connected to the other commercial line. The temperature actuated control mechanism in the instrument casing illustrated above the switch mechanism casing is connected in parallel with this circuit by a 70 connection between the upper binding post 55 in the upper instrument casing to the upper binding post 66 of the lower series in the lower instrument casing and by a connection between the lower binding posts 57 and 67. 75

As in the first instrument described the control instrument can be so adjusted that when the motor is started with the mercury tube switch in the position shown in Figure 5, the commercial current will pass through both the 80 heat generating resistance wire 40 and the series of graphite disks 10 so that if the tubular 85 member 41 remains stationary sufficient heat will pass through the resistance wire 40 to melt the solder and release the mercury tube switch to be acted upon by its counter weight to break the circuit through the motor. Under normal conditions in a domestic liquid fuel burner system the closing of the circuit to operate the motor will also ignite the 90 burner flame and the heat arising therefrom will cause the tubular member 41 to expand sufficiently to create enough pressure upon the series of graphite disks 10 to cause less resistance through the disks than through the heat wire 40 whereby the current will then 95 pass more freely through the disks and not generate sufficient heat through the resistance wire 40 to cause the solder to melt and upon the failure of the burner flame the tubular member will rapidly contract, releasing such pressure upon the series of carbon disks whereby it becomes more difficult for the current to pass therethrough and more current 100 will pass through the resistance wire which 105 will be of sufficient intensity to generate sufficient heat to melt the solder and release the mercury tube switch to break the motor circuit and causes the burner mechanism to cease 110 operation.

What I claim is:

1. In a temperature actuated electric control device including an electric switch, means normally acting to hold the switch in open position, detachable means for holding the 115 switch in closed position releasable by heat generated by the electric current, and a temperature actuated compression means for varying the current passing through said heat generated means.

2. In a temperature actuated electric control device including an electric switch, means normally acting to hold the switch in open position, detachable means for holding the switch in closed position releasable by heat 125 generated by the electric current, and a temperature actuated compression means adapted at normal temperature to actuate said means to release said switch.

3. In a temperature actuated electric con-

- tral device including an electric switch, means normally acting to hold the switch in open position, detachable means for holding the switch in closed position releasable by heat generated by the electric current, and a temperature actuated compression means adapted upon an increasing of temperature to a predetermined degree above normal to hold the switch in closed position.
- 10 4. In a temperature actuated electric control device including an electric switch, means normally acting to hold the switch in open position, detachable means for holding the switch in closed position releasable by heat generated by the electric current, and a temperature actuated means adapted upon an increase of temperature to a predetermined degree above normal to hold the switch in closed position and allow of further movement of said actuating means upon an increase of temperature above said predetermined degree.
- 15 5. In a temperature actuated electric control device including an electric switch, means normally acting to hold the switch in open position, detachable means for holding the switch in closed position releasable by heat generated by the electric current, a temperature actuated compression means adapted upon an increase of temperature to a predetermined degree above normal to hold the switch in closed position and allow of free movement of said actuated means upon an increase in temperature there above and immediately upon a lowering of temperature from any degree to actuate said means to open said switch.
- 20 6. In a temperature actuated electric control device including an electric switch, means normally acting to open said switch, detachable means for holding the switch in closed position releasable by transmitting a predetermined amount of heat thereto, and a temperature actuated compression means adapted at normal temperature to generate sufficient heat to release said holding means.
- 25 7. In a temperature actuated electric control device including an electric switch, means normally acting to open said switch, detachable means for holding the switch in closed position releasable upon application of a predetermined amount of heat thereto, electric means in the circuit with said switch adapted to apply heat to said detachable means, a pressure operated means in said circuit, a temperature control operating means for actuating said pressure operated means to generate sufficient heat to release the switch holding means.
- 30 8. In a temperature actuated electric control device including an electric switch, means normally acting to hold the switch in the closed position adapted to release said means upon the application of heat, electric heat generating means in the circuit with said switch normally adapted to generate sufficient heat to release said means, pressure operated means for reducing the amount of heat below that required to release the switch, means actuated by changes in temperature to vary the operation of said pressure means, including a plurality of superimposed graphite disks forming a part of the heat generating means in circuit with said switch, and a thermostatic element adapted to apply variable pressure thereto.

IRA E. McCABE.
